UNITED STATES PATENT OFFICE.

HUGO THUEMLER, OF SEWICKLEY, PENNSYLVANIA.

KILN FOR FIRING CHINA, GLASS, OR OTHER WARE.

SPECIFICATION forming part of Letters Patent No. 717,725, dated January 6, 1903.

Application filed October 12, 1901. Serial No. 78,514. (No model.)

To all whom it may concern:

Be it known that I, HUGO THUEMLER, of the borough of Sewickley, in the county of Allegheny and State of Pennsylvania, have invented a certain new and useful Improvement 5 in Kilns for Firing China, Glass, or other Ware, of which the following is a full, clear, and exact description, reference being had to the accompanying drawings, forming part of this specification, in which—

Figure 2 is a longitudinal vertical sectional view of my improved kiln. Fig. 1 is a cross-sectional view of the same. Fig. 3 is a vertical sectional view of a modified form, and 15 Fig. 4 is a cross-sectional view of another modification.

In the kilns now in general use for firing china, glass, or other ware great difficulty is experienced owing to the unequal and irregular 20 heating of the articles to be fired. It has been necessary to constantly watch the draft, the fire, and the fuel which is added thereto in order that the heat may in so far as possible be kept uniform.

25 The object of my invention is to secure uniform heat through every portion of the kiln and to prevent danger of irregular heating caused by over-firing or irregular firing of the kiln and at the same time to fire the ware 30 without a direct application of the flames to the object.

I will now describe my invention, so that others skilled in the art may manufacture and use the same.

35 In the drawings, *a* represents a cylindrical kiln, preferably formed of iron or other suitable metal or of tile or other refractory material, the cylinder being closed at both ends and provided with a suitable door (not shown in the drawings) for the introduction and withdrawal of the ware. This cylinder *a* is set in the brickwork of a furnace *b*, the forward end being flush with the outer face of the masonry. Around the kiln *a* is a cylindrical metal mantle *c*, which is supported 40 around the kiln by chains *d*, which extend through the top wall of the masonry *b* and pass over sheaves *e*, which are keyed to the horizontal shaft *f*, which shaft is provided

50 with a driving or band wheel *g*. In the lower portion of the masonry *b* is the fire-chamber *i*.

In the operation of this device the china or glass or other ware is placed in the stationary kiln *a*, and the door is closed. The fire being built in the fire-chamber of the masonry or furnace *b* heats the mantle *c*. The lower portion and sides being nearer the fire receive, of course, the greater heat. This mantle, however, is caused to revolve by the revolution of the shaft *f*, which imparts 60 movement to the chains *d* and causes the mantle to rotate about the kiln *a*, the mantle being thus heated equally throughout its entire surface and imparting an equal heat to 65 all portions of the cylindrical kiln.

In Fig. 3 the mantle constitutes the body of the kiln and is caused to revolve by the chains *d*, the ware being supported by suitable racks *m*, as indicated in the drawings, extending from the stationary portions or 70 ends of the kiln, which are fitted in the masonry *b*.

In Fig. 4 I have shown a modification where two kilns are placed side by side in the fire-chamber and the mantles of which are supported by rollers *k* on the power-shafts *l*. On applying power to these shafts the rollers are caused to rotate, which imparts a rotatory movement to the mantles. The power may be applied to only one of these shafts. Other 80 means may be used to revolve the mantles.

The great advantages of my invention will be apparent to those skilled in the art. A regular and uniform heat is maintained in all parts of the kiln at all times of the operation, so that the ware is not in danger of being spoiled by irregular heating.

I do not desire to limit my invention to the particular construction shown in the drawings.

Having thus described my invention, what I claim, and desire to secure by Letters Patent, is—

1. In a kiln for firing china, glass, &c., the combination of a closed chamber for holding 95 the articles, a rotatory mantle, and a fire-chamber.

2. In a kiln for firing china, glass, &c., the

combination of a rotatory mantle, means for supporting the articles, and a fire-chamber.

3. In a kiln for firing china, glass, or other ware, the combination of a cylindrical chamber, a cylindrical mantle surrounding the same, means for rotating the mantle, and a fire-chamber.

In testimony whereof I have hereunto set my hand.

HUGO THUEMLER.
